WEDDING RING

Jacob H. Schaeffer, New York, N. Y., assignor to Shiman Bros. & Co., Inc., New York, N. Y., a corporation

Application September 17, 1949, Serial No. 5,051

Term of patent 3½ years

(Cl. D45—10)

To all whom it may concern:

Be it known that I, Jacob H. Schaeffer, a citizen of the United States of America, and a resident of the city of New York, in the county of Kings and State of New York, have invented a new, original, and ornamental Design for a Wedding Ring, of which the following is a specification, reference being had to the accompanying drawing, forming a part thereof.

Fig. 1 is an enlarged top view of a wedding ring showing my design, and

Fig. 2 is a side view thereof.

The dominant portion of my design resides in the portions shown in full lines.

I claim:

The ornamental design for a wedding ring, substantially as shown and described.

JACOB H. SCHAEFFER.
